US0D1037965S

(12) **United States Design Patent** (10) **Patent No.:** **US D1,037,965 S**
(45) **Date of Patent:** **** Aug. 6, 2024**

(54) **WHEEL**

(71) Applicant: **Zoox, Inc.**, Foster City, CA (US)

(72) Inventors: **Timothy David Kentley-Klay**,
Stanford, CA (US); **Nahuel Elias Battaglia**, Stanford, CA (US); **Herman Francisco Delos Santos**, Redwood City, CA (US); **Richard Luke Osellame**, Redwood City, CA (US); **Christopher John Stoffel**, San Carlos, CA (US)

(73) Assignee: **Zoox, Inc.**, Foster City, CA (US)

(**) Term: **15 Years**

(21) Appl. No.: **29/836,347**

(22) Filed: **Apr. 26, 2022**

Related U.S. Application Data

(63) Continuation of application No. 29/655,151, filed on Jun. 29, 2018, now Pat. No. Des. 954,626.

(57) **CLAIM**

The ornamental design for a wheel, as shown and described.

DESCRIPTION

FIG. 1 is a front perspective view of a wheel showing the claimed design;

FIG. 2 is a left-side view thereof;

FIG. 3 is a right-side view thereof;

FIG. 4 is a front view thereof;

FIG. 5 is a back view thereof;

FIG. 6 is a top view thereof; and,

FIG. 7 is a bottom view thereof.

The dashed broken lines depict portions of the wheel that form no part of the claimed design.

1 Claim, 7 Drawing Sheets
